UNITED STATES PATENT OFFICE.

EMIL POUYAT, OF LIMOGES, FRANCE.

DESIGN FOR A DISH.

SPECIFICATION forming part of Design No. 19,742, dated April 1, 1890.

Application filed December 23, 1889. Serial No. 334,795. Term of patent 14 years. Registered in France October 14, 1889, No. 276.

To all whom it may concern:

Be it known that I, EMIL POUYAT, a citizen of France, residing at Limoges, in the Department of Haute-Vienne, France, have invented and produced a new and original Design for Dishes, of which the following is a specification, reference being had to the accompanying drawings, forming a part thereof.

Figure 1 is a profile view of a soup-tureen or covered dish. Fig. 2 is a face view of a cover. Fig. 3 is a face view of a platter or deep dish. Fig. 4 is a face view of a plate, these four views being deemed necessary to illustrate my design.

The leading feature of my design consists in presenting on the given ware the resemblance of satin folded or plaited.

The form of the soup-tureen or covered dish, Fig. 1, is square. The plaits in the satin are represented by the lines A on the cover and body of the dish. The handles B B B are made to represent bows or loops of ribbon knotted at one end. One of the loops, as seen by Fig. 2, forms the handle. At the end where

the knot is tied, C C C, there is bound by the 25 ribbon a bunch of forget-me-nots. From the knot the two ends of ribbon fall to the side in curves. The platters or deep dishes, Fig. 3, are also square, and have the same satin folds E E E as the covered dishes. At the two 30 ends are handles having in relief the same design as above described.

The plates, Fig. 4, are round and plain. Only the rim F is plaited to resemble satin. The center G of the plate is perfectly smooth 35 and plain.

What I claim is—

1. The design for dishes herein shown and described.
2. In the design for dishes herein shown 40 and described, the handles B B B, representing bows or loops of knotted ribbon inclosing a bunch of forget-me-nots.

EMIL POUYAT.
